COMBINED LOUNGE AND TABLE UNIT

John E. McRee, Irving, Tex., assignor to Shampaine Industries, Inc., St. Louis, Mo., a corporation of Missouri

Filed Mar. 25, 1963, Ser. No. 74,123

Term of patent 7 years

(Cl. D15—11)

FIG. 1 is a front perspective view of a combined lounge and table unit embodying my new design; and

FIG. 2 is a rear perspective view thereof.

I claim:

The ornamental design for a combined lounge and table unit, substantially as shown.
